UNITED STATES PATENT OFFICE.

A. W. HALL, OF NEW YORK, N. Y., ASSIGNOR TO HIMSELF, R. K. BELDEN, AND SAMUEL GAUDON, OF SAME PLACE.

IMPROVED AMALGAMATOR.

Specification forming part of Letters Patent No. 44,140, dated September 6, 1864.

To all whom it may concern:

Be it known that I, A. W. HALL, of the city, county, and State of New York, have invented a new and useful Improvement in Amalgamators; and I do hereby declare that the following is a full, clear, and exact description thereof, which will enable those skilled in the art to make and use the same, reference being had to the accompanying drawings, forming part of this specification, in which—

Figure 1 is a side view of my invention; Fig. 2, a horizontal section of the same, taken in the line *x x*; Fig. 1; Fig. 3, a back view of a part pertaining to the same.

Similar letters of reference indicate corresponding parts.

This invention relates to a new and improved apparatus or device for more effectually separating gold and silver from the crushed ore, or "pulp," as it is frequently termed among miners.

The invention is applicable to what is known as the "Chilian crushing mill," or to any of the ordinary amalgamating pans in which a rotary muller is employed—in fact, it may be used in all cases where gold and silver is separated from the pulp by means of stirring and agitating the latter in connection with amalgamated metal surfaces.

The invention consists in the employment or use of a series of amalgamated plates, secured at proper distances apart and connected with any suitable moving parts, which will admit of the amalgamated plates being drawn through the pulp, as hereinafter set forth.

A represents a wheel, which may be constructed of cast-iron and formed with a broad tread or periphery, *a*, extending some distance each side of the body or main portion *b*. To each side of the body or main portion *b* of the wheel there are attached a series of copper plates, *B*, which may be in the form of quadrants, and secured to *b* by means of bolts *c*, having washers *d* on them to keep them at a proper distance apart and admit of a free or open space between the several plates, so that both sides of each, except the inner ones, which are in contact with *b*, may be brought in contact with the pulp, a space, *e*, being allowed between the edges of the several sets of plates, as shown in Fig. 1, to admit of the

free passage of the pulp between the plates. Any number of these plates *B* may be used in Fig. 2. Three are shown composing each set.

The wheel *A*, when the invention is applied to what is known as the "Chilian mill," may form the crushing-wheel, and thereby perform two functions—to wit, a crusher and an amalgamator. The copper plates *B*, previous to being used, have their surfaces properly amalgamated with quicksilver, and the wheel *A*, while being drawn around the annular trough containing the pulp and quicksilver, will cause the plates *B* to pass through the latter, and said plates will catch and amalgamate all the particles of gold which may come in contact with them. Thus it will be seen that I obtain an amalgamating device which may be used in addition to what is now employed, and without monopolizing any additional space or room, and owing to this arrangement the gold contained in the pulp will be effectually separated from it, the fine particles, which are light and rise to the surface and frequently pass out with the water, being arrested and amalgamated with the plates *B*.

In order to render the invention more complete or perfect, I employ what may be termed a "drag," the same being composed of a series of horizontal copper plates, *C*, which are secured one above the other by bolts *f*, having washers *g* on them, to keep the plates *C* at a proper distance apart. The bolts *f* pass through a bottom plate, *h*, which may be of cast-iron and curved upward in front to admit of it freely passing over the bottom of the pan or trough, and said bolts also pass through a top plate, *i*, which may also be of cast-iron, and is wider than the copper plates *C*, (see Fig. 3,) in order to protect the latter from the sides of the trough in case of the tilting of the device. This drag may be connected to the axle *j* of the wheel *A*, or connected to any moving part of the device to enable it to be drawn through the pulp. The plates *C* also serve to catch and arrest the fine particles of gold in the pulp, preventing them from floating on the pulp and passing off with the wash or water.

I claim as new and desire to secure by Letters Patent—

The employment or use, in a gold or silver

amalgamating device, of a series of amalgamated plates placed or secured at proper distances apart, so as to allow the pulp to pass freely between them, and attached either to a crushing-wheel or drag, so that they may, during the amalgamating process, be drawn through the pulp and catch or arrest and

amalgamate the fine particles of gold or silver contained therein, substantially as herein set forth.

A. W. HALL.
